UNITED STATES PATENT OFFICE.

JOSEPH L. STENGEL, OF CINCINNATI, OHIO, ASSIGNOR TO UNION SPECIAL MACHINE COMPANY, OF CHICAGO, ILLINOIS, A CORPORATION OF ILLINOIS.

STOCKING-GUIDE FOR SEWING-MACHINES.

1,339,230.

Specification of Letters Patent.

Patented May 4, 1920.

Application filed September 7, 1917. Serial No. 190,161.

To all whom it may concern:

Be it known that I, JOSEPH L. STENGEL, a citizen of the United States, residing at Cincinnati, in the county of Hamilton, State of Ohio, have invented certain new and useful Improvements in Stocking-Guides for Sewing-Machines, of which the following is a description, reference being had to the accompanying drawing and to the figures of 10 reference marked thereon.

The present invention relates to sewing machines and especially to a guide for use in connection therewith, for guiding a circular knit stocking to the stitch forming 15 mechanism, whereby when sewed with a line of overseaming stitches said stocking has the appearance of a full fashioned article.

It is well known that a full fashioned stocking knit upon a flat frame with its 20 selvage edges seamed together holds its shape better than a circular knit stocking. However, by stitching a seam along the back of a circular knit stocking it not only affords a perfect imitation of a full fashioned 25 stocking but as a matter of fact, the seam serves to hold it in shape better under the strain of putting on and pulling off.

In making this imitation full fashioned hose, however, while sewing machines as ordinarily equipped work satisfactorily so far as the actual stitching is concerned, it is difficult in practice to guide the fabric properly and to prevent the work being spoiled in appearance by having several of the wales 35 thereof crossed in the operation. Neat work requires that the stitching must extend in a straight line parallel to certain wales of the fabric.

The present invention, therefore, consists 40 of a guide having a free end over which the stocking is drawn, and formed in two parts one of which is rigid and enters between two adjacent wales of the fabric while the other member is pivoted and by its weight holds 45 the tube slightly extended downward. The free end of the guide is brought as close to the needle as is possible and is held in the space between the cup feeds on a machine of the type shown in the patent granted 50 Lansing Onderdonk, September 5th, 1916, #1,197,055, and known as the Union Special machine, style, 41,000.

The invention is hereinafter described and

referred to in the appended claims and is illustrated in the accompanying drawings, 55 in which,

Figure 1 is a perspective view of a portion of a cup feed sewing machine with my improved stocking guide located in relation thereto, the stocking being shown as partially seamed;

Fig. 2 is a side view of the stocking guide showing the position of the two parts when the stocking is drawn on;

Fig. 3 is a similar view, showing the 65 pivoted member dropped by gravity to distend the stocking;

Fig. 4 is a sectional view on the line 4—4 of Fig. 3;

Fig. 5 is a cross section of the stocking 70 provided with the seam.

Fig. 6 is a detail view of the link for holding the parts of the guide parallel when the stocking is being drawn on the same or when the guide is not in use.

In the drawings, the sewing machine is 75 of the cup feed type as illustrated in the aforesaid Patent, 1,197,055 and the casing 1, needle 2, looper 3, cup feed devices 4 and the various guides and other parts are similar to those shown in the patent referred to 80 and need not be specifically described.

It will be understood also that the outer cup feed may be moved laterally to allow the insertion of the work. The guide itself 85 comprises a standard 5 to which is secured in a socket a vertical rod 6 which may, if desired be rotatably mounted in the socket so that the guide as a whole may be swung laterally. Attached to this rod 6, as by 90 screws 7, is a horizontal flat arm or plate 8, which has a pointed forward end 9 which extends between the feed cups 4 in close proximity to the needle so that the fabric is properly guided by the ordinary guide of the sewing machine to the stitch forming mechanism. Pivoted to the horizontal arm at the point 10 is an arm 11 which normally by gravity assumes a position lower than the horizontal arm 8. In operation the two 95 arms are brought together and a circular knit stocking is slid over the arms. The pivot arm 11 then acts by gravity upon the stocking and distends the same downwardly, thus causing the upper edge of the stocking 100 to closely hug the upper edge of the horizon- 105

tal arm 8. The operative will then see that one of the wales of the stocking follows along the upper edge of the horizontal arm so that the seam which is sewed by the stitch forming mechanism will follow a defined line along the adjacent wales of the goods so that there will be no crossing of the wales by the stitching. The seam formed in the stocking will be of the ordinary overseaming type, will be substantially flat and will afford a perfect imitation of a perfect full fashioned stocking. Furthermore, the seam will add to the strength of the fabric and prevent the stretching out of shape of the completed stocking in pulling on or taking off.

In Fig. 6 is shown at L a link which is carried on the rigid portion of the guide and serves to hold the rigid and pivoted portion of the guide together in parallel relation when the device is not in use and also when the stocking is being drawn upon the guide. In the latter operation the link is pushed forward on the guide to hold the parts in parallel relation, the stocking is drawn over the end of the guide and when it has been properly set, the link is withdrawn from engagement with the pivoted portion, allowing the latter to drop.

While I have shown this stocking guide as applied to a machine of the special type above referred to and it is of special use in connection therewith, I wish to be understood that so far as the guide itself is concerned, it may be used in connection with other types of sewing machines.

Having thus described my invention, what I claim is:—

1. In combination with a sewing machine having devices for feeding a vertically arranged fabric and having overseaming mechanism including a horizontal needle, a stocking guide having a rigid guiding portion over which the stocking is drawn with the upper edge of the guiding portion between two wales of the stocking, said guiding portion extending in close proximity to the stitching mechanism, and a movable part cooperating with the rigid part to distend the stocking vertically, whereby the stocking may be delivered throughout its full length in a defined line to the stitching mechanism.
2. In combination with a sewing machine having horizontally arranged feeding wheels for feeding a vertically arranged fabric and

having overseaming mechanism including a horizontal needle, of a stocking guide having a rigid guiding portion over which the stocking is drawn with the upper edge of the guiding portion between two wales of the stocking and extending between the feed wheels and in close proximity to the stitching mechanism and a movable part co-operating with the rigid part to distend the stocking vertically whereby the stocking may be delivered throughout its full length in a defined line to the stitching mechanism.

3. A guide for delivering a knitted tube to stitching mechanism including a rigid horizontal arm over which the tube is drawn and set with the upper edge of the guide between two wales of the fabric, and a pivoted arm attached to the rigid arm for distending the tube downwardly and holding it in stretched position.

4. A guide for delivering a knitted tube to stitch-forming mechanism including a vertical standard, a rigid horizontal arm having a pointed end adapted to enter between two adjacent wales of the fabric and a pivoted gravity operated arm adapted to distend the tube downwardly.

5. A guide for delivering a knitted tube to stitching mechanism including a rigid horizontal arm over which the tube is drawn and set with the upper edge of the guide between two wales of the fabric, a movable arm co-operating with the rigid arm for distending the tube downwardly and holding it in stretched position, and means slidably mounted on said rigid arm for holding the movable arm in parallelism therewith when placing a stocking therearound.

6. A guide for delivering a knitted tube to a stitch forming mechanism including a supporting standard, an arm over which the tube is drawn fixedly secured to the standard and having its free end disposed in co-operative relation to said stitch forming mechanism, an arm pivoted to the fixed arm for distending the tube downwardly, and means for holding said pivoted arm in parallelism with the fixed arm for permitting the tube to be positioned therearound.

In testimony whereof I affix my signature, in the presence of two witnesses.

JOSEPH L. STENGEL.
